UNITED STATES PATENT OFFICE.

KARL A. BECKER, OF LOS ANGELES, CALIFORNIA.

VIOLINIST'S PRACTICE DEVICE.

1,275,202.

Specification of Letters Patent. Patented Aug. 13, 1918.

Application filed October 8, 1917. Serial No. 195,250.

To all whom it may concern:

Be it known that I, KARL A. BECKER, a citizen of Switzerland, having declared my intention of becoming a citizen of the 5 United States, residing at Los Angeles, in the county of Los Angeles and State of California, have invented a new and useful Violinist's Practice Device, of which the following is a specification.

10 This invention relates to devices of the character designed to aid violin students in learning to properly hold the violin and to properly manipulate the bow thereof.

An object of the invention is to produce 15 a device in which the position and manipulation of the bow may be caused to exactly correspond with the correct position and manipulation thereof in the playing of a violin.

20 Another object is to afford means for the strengthening of the muscles of the fingers used in stopping.

Another object is to make provision for both a positive guiding and a non-positive 25 guiding of the bow. By "positive guiding" is meant the constraining of the bow on three sides during the bowing operation, and by "non-positive guiding" is meant the constraining of the bow on two sides only 30 during the bowing operation. When the bow is constrained on but two sides, if it be not moved accurately at right angles to the body of the device, it will slip off of the guiding means. The positive guiding prevents mistakes in the bowing and the non-positive guiding permits mistakes to be made in the bowing but reveals that the mistake is made.

35 Other objects and advantages will appear in the subjoined detail description.

40 The accompanying drawings illustrate the invention:

Figure 1 is a perspective view of a device embodying the invention.

Fig. 2 is a plan view of Fig. 1, omitting the 45 bow.

Fig. 3 is a longitudinal sectional view on line indicated by x^3-x^3 , Fig. 2, the bow also being shown in section in one of its bowing positions.

50 Fig. 4 is a sectional elevation on line indicated by x^4-x^4 , Fig. 3.

Fig. 5 is a sectional elevation on line indicated by x^5-x^5 , Fig. 3.

Fig. 6 is a fragmental sectional detail of the bow guide, bow, and a fragment of the 55 body, said bow guide and bow being differently positioned than in Fig. 3.

The invention comprises a substantially straight bar forming a body 1, a neck 2, and a head 3 joined to said body by the neck. 60 The neck and head 2, 3 are of the same shape as the neck and head of the usual violin. At the end of the body 1 opposite its connection with the neck 2 is a chin rest 4 formed, in the instance shown, by a flat member extending substantially at right angles from the body. The chin rest 4 is provided along its upper end at the outer end thereof with an upwardly extending rounded shoulder 5 adapted to fit against the left-hand side of 65 the jaw of the violin student using the device. The chin rest 4 together with its shoulder 5 thus forms a guide whereby correct positioning of the inner end of the instrument is insured.

75 The neck 2 may, if desired, be provided with recesses 6 in which are seated cylinders 7 containing plungers 8, said plungers normally being pressed upward against the outer ends 9 of the cylinders by springs 10 80 inserted between the bottoms of the recesses and said plungers. The plungers 8 are sufficiently long to obtain good bearing in the cylinders so as to work smoothly. The ends 9 of the cylinders are provided with perforations 11 through which extend stems 12 connected to the plungers 8, the outer ends of said stems being provided with knobs 13. Thus the plungers 8, stems 12 and knobs 13 together constitute yieldingly mounted keys. 90

85 There are preferably four keys, one for each of the four fingers of the left hand of the violin student using the device. When the device is in use, it is clear that the operation of the keys against the pressure of the 95 springs 10 will develop the muscles of the fingers used in stopping when playing a violin. These keys are so arranged that they represent certain playing positions of the fingers of the left hand so that in effect they 100 form guides for said fingers for the correct positioning of the fingers to obtain certain notes from a violin.

105 Mounted on the body 1 is a bow guide indicated in general at 14 and provided in its upper portion with a slot 15 extending trans-

versely of the body, the slot being formed between side walls 16 of the guide. The bottom of the slot 15 may be convex from end to end as shown at 17 in Fig. 4, the curvature substantially corresponding to that of the bridge of a violin so that certain points on the slot bottom 17 will exactly correspond to the various positions of the strings of a violin relative to the chin and left hand of 10 the student using the instrument, and this is insured by the fact that the bottom 17 of the slot is above the level of the upper face of the body.

The slot 15 is adapted to receive a bow 18 which may be in the form of a flat rod or stick slightly thinner than the width of the slot so that the bow can be freely moved endwise in the slot without binding when it is moved parallel to the side walls 16. It 20 is clear that if the bow is not moved endwise in exact parallelism with the wall 16 friction will arise between said bow and side walls so that the bow can only be moved with difficulty. Preferably a thumb notch 25 19 is provided in one edge near one end of the bow.

Preferably there projects a shoulder 20 from that side of the bow guide 14 turned toward the head 3, and the upper edge 21 30 of said shoulder is preferably convex transversely of the body 1 similar to the bottom 7 of the slot 15. Preferably also the edge 21 of the shoulder slopes downward and outward, as clearly shown in Fig. 6.

35 The bow guide would be useful, even though stationarily mounted on the body 1, but in order that desirable adjustments of the bow guide may be made, the body may be provided with a slot 22 extending lengthwise of the body, and a clamping screw 23 extends through said slot and is screw-threaded into the bow guide 14. On the screw 23 is a washer 24 adapted to be pressed into engagement with the under face 40 of the body 1 by a thumb nut 25 on the outer end of the screw 23. The slot 22 is preferably of such length that when the screw 23 rests against the forward end of the slot which thus forms a stop, as in Fig. 4, the 45 position of the bow 18 in the slot 15 relative to the body 1 will exactly coincide with the position of said bow when the screw 23 engages the rear end of the slot 22 and the bow rests on the boss 20, as in Fig. 6. The 50 bottom of the bow guide 14 is provided with a groove 26 to fit the body. The 55

In practical use the violin student will place the instrument in position with the upper edge of the chin rest 4 beneath the 60 chin and the shoulder 5 thereof against the left-hand side of his jaw, and he will grasp the neck 2 in the left-hand, placing the ends of the fingers on the keys. Assuming that the bow guide 14 is in the position shown 65 in Figs. 2 and 3, he will grasp the bow with

the right-hand, placing his thumb in the notch 19, and he will move the bow endwise in the slot 15 and will manipulate the bow in the manner customary in playing a violin.

When the student has acquired facility in 70 bowing in the slot 15 and can move the bow endwise with perfect freedom so that no binding of the bow in the slot occurs, the thumb screw 25 will be loosened and the bow guide 14 shifted to the position shown 75 in Fig. 6. The student will then place the bow on the shoulder 20 and manipulate the bow as before. It is noted that in this last bowing position, if the bow be not operated substantially parallel to the wall 16 the bow 80 cannot be held on the shoulder 20. It is also noted that owing to the slanting edge of the shoulder, it is necessary for the student to constantly press the bow toward the wall 16 so as to prevent it sliding down the 85 inclined edge and off of the shoulder.

Thus it is clear that when the bow is in the slot 15 it will be positively guided by the walls 16, and that when the bow rests on the shoulder 20 it will be non-positively 90 guided, that is to say, as long as it is moved correctly it will stay on the shoulder but when it slips from the shoulder such slipping will indicate to the student that he is not moving the bow correctly. 95

I claim:

1. A violinist's practice device comprising a body, a neck connected with said body, a bow guide projecting up from the body and provided with a slot extending transversely of the body, the bottom of the slot being above the level of the upper face of the body and being curved like the upper edge of a violin bridge, and a bow fitted to work in said slot. 100

2. A violinist's practice device comprising a body, a neck connected with said body, and a member projecting up from the body and provided with a shoulder on one side adapted to support a bow. 110

3. A violinist's practice device comprising a body, a neck connected with said body, a bow guide projecting up from the body and shiftably mounted thereon and curved like the upper edge of a violin bridge, means 115 to hold the bow guide against shifting, and a bow fitted to work in the bow guide.

4. A violinist's practice device comprising a body, a neck connected with said body, a member projecting up from the body and shiftably mounted thereon and provided with a slot and with a shoulder, and means to hold the bow guide in different positions along the body so that a bow can be used in the slot or on the shoulder when the slot 120 and shoulder occupy the same positions relative to the violinist's shoulder as he uses the device. 125

5. A violinist's practice device comprising a body, a neck connected with said body, 130

a bow, a guide on the body for the bow, and yieldingly mounted keys in the neck for the stopping fingers of the student.

6. A violinist's practice device comprising
5 a body, a neck connected with said body, and a member projecting from the body and having a shoulder on one side thereof, the upper edge of said shoulder being a slant

downward and outward and said shoulder being adapted to support a bow. 10

Signed at Los Angeles, California, this
1st day of October, 1917.

KARL A. BECKER.
